UNITED STATES PATENT OFFICE

EDWARD E. SCHLEICHER, OF PROVIDENCE, RHODE ISLAND

DESIGN FOR A NECKLACE PENDANT OR OTHER JEWELRY FOR PERSONAL USE

Application filed March 17, 1931. Serial No. 39,128. Term of patent 3½ years.

To all whom it may concern:

Be it known that I, EDWARD E. SCHLEICHER, a citizen of the United States of America, residing in Providence, county of Providence, State of Rhode Island, have invented a new, original, and ornamental design for a Necklace Pendant or Other Jewelry for Personal Use, of which the following is a specification, reference being had to the accompanying drawing, forming a part thereof.

Fig. 1 is a plan view; and

Fig. 2 is a section on line 2—2 of Figure 1 of a necklace pendant or other jewelry for personal use, showing my new design.

The figure is flat, of contrasting color to the marginal portion, and is inset into the base to be flush with the marginal portion.

I claim:

The ornamental design for a necklace pendant or other jewelry for personal use, substantially as shown and described.

EDWARD E. SCHLEICHER.
